COMPOSITION TOP SOLE

Benjamin Gilowitz, Bronx, N. Y., assignor of one-fourth to Albert Friedberg, Bronx, N. Y., and twelve and one-half per cent to Horatio D. Minter and twelve and one-half per cent to Robert J. Grilfoyle

Application December 2, 1939, Serial No. 307,328

2 Claims. (Cl. 36—32)

The invention relates to composition top soles of the general type usually cemented to worn shoe soles.

One object of the invention is to provide a novel composition sole having a forwardly thickened tip to compensate for wear at the tip of a worn shoe sole.

Another object is to provide a composition sole having a channel near its edge which facilitates cutting edge portions from the sole to leave only thin, preferably beveled edges thereon, for disposition in inwardly spaced relation with the edge of the worn shoe sole, giving a better appearance than if the top sole extended entirely to the edge of the old sole.

Yet another object is to make novel provision for securing the tip portion of the top sole to the old sole with unusual tenacity.

With the foregoing in view, the invention resides in the novel subject matter hereinafter described and claimed, description being accomplished by reference to the accompanying drawing.

Figure 1 is a bottom plan view showing one form of construction.

Figures 2 and 3 are sectional views on lines 2—2 and 3—3 of Fig. 1.

Figure 4 is a view similar to Fig. 1 but showing the top sole with the edge portions cut off.

Figure 5 is a partial bottom plan showing a different construction.

Figure 6 is a disassembled perspective view of the form shown in Fig. 5.

Figure 7 is a diagram showing the un-cured blanks which may be used in manufacturing the top sole.

In Figs. 1 to 4, a composition sole 10 is shown suitably designed at 11 and 12 for anti-slipping purposes, said sole having a forwardly thickened tip 13 which is preferably of harder material than the rest of the sole, providing for greater durability where a large part of the wear is concentrated. The tip portion 13 is adapted to compensate for wear at the tip of an old or worn shoe sole, and while it is intended that the entire top sole be cemented to the old sole, it is preferable to provide said tip portion with small openings or indentations 14 to facilitate driving of small nails or screws to additionally secure the tip to the shoe.

The lower side of the top sole 10 is provided near its longitudinal edges with shallow channels 15, letting longitudinal edge portions 16 to be cut off either before or after applying the sole to the shoe. The upper side 17 of each channel 15 is

disposed at such a height as to leave only very thin edges on the top sole after the edge portions 16 are cut therefrom. Preferably the channel sides 17 are outwardly inclined to leave beveled or feather edges upon the top sole, merging the latter well into the edge portions of the old sole. The outer sides 18 of the channels 15 are preferably vertical or abrupt to guide the knife or other tool used in cutting the edge portion 16 from the sole 10. It is preferable also that the edge portions 16 be outwardly beveled or feathered, not only to economize in material, but to permit the entire sole 10 to be applied to a shoe if desired, without cutting the edge portions 16 from the major portion of said sole 10. Moreover, it is desirable to have the edge of the tip 13 and the longitudinal edges of the portions 16 continuous with each other, whether the portions 16 are to be removed or left on the top sole 10, as this construction facilitates trimming of the usual web or mould overflow from the edge of the completed soles, with conventional machines.

In Figs. 5 and 6, a sole 10^a is shown which is very similar to the sole 10. At the juncture of the triangular tip portion 13^a with the major portion of the top sole, the lower side of the latter is provided with rearwardly converging grooves 12^a, and a similar groove 12^b is formed in the front portion of the tip portion 13^a. A tip protecting and securing member 19 is provided with a rearwardly projecting portion 20 received in the groove 12^b, and with rearwardly converging portions 21 received in the grooves 12^a, all of said portions having small openings 22 through which to drive attaching nails or screws to securely attach the top sole to the shoe. The member 19 is provided with an arcuate rim 23 which extends upwardly from the top sole 10^a to engage the edge of the old shoe sole at the tip of the latter, and the upper edge of said rim 23 may well be provided with inwardly projecting lugs 24 to lie upon the usual projecting sole edge or welt. Small openings 25 are preferably formed in the lugs 24 to receive minute attaching tacks or nails. The member 19 may of course be formed from metal or any other desired material.

In Fig. 7, I have illustrated a blank of composition sole-forming material at 26, said blank being formed with a V-shaped notch 26^a in its front end. I have also illustrated a substantially triangular blank 27 which may be formed of the same composition or other preferred composition, the rear end of 27 being receivable in 26^a. The two pieces are then placed in a mould and cured so that they become one unitary piece, provid-

ing a top sole such as 10 or 10^a and a tip such as 13 or 13^a. The compositions from which 26 and 27 are formed, or the composition from which they both may be formed, are preferably such that the tip 27 will be harder and more wear-resisting than the top sole, in the completed article, placing the wear-resisting part where the most wear comes and the flexibility where yielding is necessary. The relatively tough tip also 10 permits use of one or more nails or screws in securing it to the old sole.

From the foregoing taken in connection with the accompanying drawing, it will be seen that novel and advantageous provision has been made 15 for carrying out the objects of the invention. While preferred details have been illustrated, attention is invited to the possibility of making variations within the scope of the invention as claimed.

20 I claim:

1. A composition top sole having a forwardly thickened tip to compensate for wear on the tip of a worn shoe sole, the greatest thickness of 25 said forwardly thickened tip being at the front extremity of the top sole, the bottom of said top sole having channels spaced inwardly from its longitudinal edges and extending from the rear end or shank of said top sole to said forwardly

thickened tip, leaving longitudinal edge portions to be cut off to space the major portion of the top sole inwardly from the edges of a worn shoe sole, the rear ends of the edge of said forwardly thickened tip being spaced outwardly from said 5 channels to extend flush with the edge of a worn sole tip when said longitudinal edge portions have been cut off and said major portion is inwardly spaced from the longitudinal edges of the worn sole, the upper sides of said channels 10 being inclined outwardly to leave beveled edges on the top sole when the aforesaid longitudinal edge portions are cut off, the outer walls of said channels being abrupt to guide the knife or other tool used in cutting off said edge portions. 15

2. A composition top sole having a channel in its bottom spaced inwardly from its edges, leaving edge portions to be cut off to space the top sole inwardly from the edge of the old shoe sole, the upper side of said channel being outwardly 20 inclined throughout its width to leave beveled edges on the top sole when the aforesaid edge portions are cut off, the outer wall of said channel being abrupt and substantially perpendicular to the bottom of the top sole to guide the knife 25 or other tool used in cutting off said edge portions.

BENJAMIN GILOWITZ.
